UNITED STATES PATENT OFFICE.

GUSTAVE ALLISON, OF PERTH AMBOY, NEW JERSEY, ASSIGNOR TO COLUMBIA SALVAGE CORPORATION, OF NEW YORK, N. Y., A CORPORATION OF NEW YORK.

METHOD AND APPARATUS FOR SALVAGING ARTILLERY AMMUNITION.

Application filed December 8, 1924. Serial No. 754,591.

To all whom it may concern:

Be it known that I, GUSTAVE ALLISON, a citizen of the United States, and resident of Perth Amboy, in the county of Middlesex and State of New Jersey, have invented certain new and useful Improvements in Methods and Apparatus for Salvaging Artillery Ammunition (Case 17), of which the following is a specification.

10 This invention relates to the art of salvaging artillery ammunition and more particularly to the salvaging of the explosive propelling charges for trench mortar shells. The explosive charge used in trench mortars is known as ballistite, a smokeless powder well adapted for sporting ammunition and therefore possessing considerable commercial value. The ballistite when prepared for artillery use is confined in small tubular 15 silk bags approximately one half inch in diameter and four inches long. Each bag has its ends stitched together and forms a ring adapted to be threaded over the tail piece of a trench mortar shell. Twelve of 20 such rings constitute the propelling charge for a shell. For transportation and storage the rings are packed in sealed sheet metal containers each holding twelve rings or a single propelling charge. In order to 25 recover the ballistite it is necessary to remove the rings from the sheet metal containers and to remove the ballistite from the silk bags.

30 One of the objects of the invention is to provide a method and apparatus for safely and rapidly recovering large quantities of the powder from its enclosing bags and containers and preparing it for commercial use.

35 A further object is to provide a method and apparatus for facilitating the handling of the work from its arrival at the salvaging plant to the shipment of the recovered powder therefrom.

40 In the drawings:

Fig. 1 is a diagrammatic side view of the means for carrying out the invention;

Fig. 2 a diagrammatic side view thereof;

50 Figs. 3 and 4 views showing the manner of opening the sheet metal containers;

Fig. 5 a side view of a trench mortar shell with a propelling charge of ballistite rings mounted upon it and shown in section;

Fig. 6 a detail view of one of the ballistite rings upon a larger scale;

Fig. 7 a sectional view illustrating the means for cutting open the rings or bags, and the conveyors connected thereto;

Fig. 8 a detail sectional view of a portion of the conveying means delivering to the bag opening means;

Fig. 9 a sectional view showing the means for separating the powder from the opened bags, and the conveyors connected thereto;

Fig. 10 a sectional view illustrating the screening means for removing the lint from the powder, and the conveyors connected to said means;

Fig. 11 a plan view thereof; and

Fig. 12 a sectional view through the means for charging the powder into sacks and weighing it.

Referring to the parts by numerals, 1 designates a railroad track, and 2 an unloading platform adjacent the track and formed with a number of branches 3. Upon each branch platform 3 is mounted a pair of spaced hooks 5 adapted to serve as holders for the containers C. These containers 80 are substantially cylindrical and formed in two halves secured together by a sealing band which encircles the container and is soldered over the meeting edges of the container halves. The sealed containers full of ballistite rings are unloaded upon the platform 2 from a railroad car and each container is placed back of the hooks 5 with its sealing band B between the hooks. The free end of the sealing band is then gripped 90 by a pair of pliers, as shown in Figs. 3 and 4, and a straight outward pull exerted upon it, causing the container to be rotated and the band stripped therefrom to open the container.

The ballistite rings R (one of which is shown in Fig. 6) are emptied from the opened containers into a suitable receptacle, which is pushed over a roller conveyor 6 extending adjacent the platform 2, and are 100 emptied into a hopper 7. The hopper 7 delivers to an endless conveyor 8 which is driven by an electric motor 9 and delivers the rings upwardly to a chute 10 leading to the hopper of a cutting machine 11. This 105 machine includes a casing having a number of fixed blades mounted therein and a rotor 13 carrying a number of blades 14 adapted

to move past the fixed blades and cut open the silk bags or rings R. The rotor is driven by an electric motor 15 and the spaces between the blades of the rotor are bridged by plate 16 which prevent the rings from dropping through the rotor and emerging from the machine uncut. The opened bags and the powder pass out of the cutting machine through a chute 16 and fall upon an endless conveyor 17. The conveyor 17 is driven by an electric motor 18 and carries the mixture of powder and bags upwardly to deliver them into a chute 19 leading to the hopper 20 of a machine for separating the powder 15 from the bags. This machine comprises a substantially cylindrical screen 21 open at both ends and adapted to rotate on an inclined axis. The chute 20 delivers into the upper open end of the screen. The screen 21 is rotated by an electric motor 22 and as the powder and bags, delivered through the chute 20, pass downwardly within the screen the powder is shaken from the open bags and passes through the mesh of the screen 25 into a chute 23. The lower end of the chute 23 has a delivery opening adapted to deliver the powder through a manually operable valve 24 to a receptacle placed upon a roller conveyor extending beneath the chute. The 30 emptied bags pass out through the lower end of the screen and through a discharge chute 26.

The receptacle with the separated powder is next pushed over the conveyor 25 to 35 deliver the powder to an oscillating screen 27 of finer mesh than the screen 21. The screen 27 removes any lint which may have been left in the powder and the screened powder passes through a chute 28 beneath 40 the screen and into a receptacle placed upon a roller conveyor 29. The screen 27 is oscillated by an eccentric connection 30 driven by an electric motor 31. The powder is now in a condition for commercial use and is moved in its receptacle 45 over the conveyor 29 and delivered into an elevated hopper 32 located upon a train loading platform 33 adjacent the track 1. The hopper 32 is located over the platform of 50 weighing scales 34 and is adapted to deliver the powder through a manually operated valve or gate 35 into paper sacks of suitable size placed upon the scale platform. The powder is weighed in the sacks, packed for 55 shipment upon the platform 31, and loaded upon a car alongside of the platform.

The various operations are performed at 60 widely spaced points in order that in case of a fire occurring at any point through carelessness, it will be prevented from spreading to the other points of operation. The various conveyors provide for quickly and easily moving the work from one operation to another and the entire system is designed 65 to facilitate the performance of the opera-

tions and the handling of the work from its arrival to the reshipment of the powder. The continuously driven conveyors 8 and 17, owing to their inclination and length, are adapted to deliver the powder and bags to 70 the rotary cutter and to the rotary screen respectively in the form of a continuous attenuated stream. This prevents clogging of the cutter and screen and ensures their efficient operation. By the use of a system such as that shown and described an enormous quantity of powder has been salvaged within an extremely short space of time and without the employment of skilled or specially trained labor. 80

What I claim is:

1. The method of salvaging explosive powder contained in small fabric bags, consisting in delivering the bags in a continuous attenuated stream into an apparatus to open the bags, continuously operating said apparatus, delivering the opened bags and powder in a continuous attenuated stream from the bag opening apparatus into an apparatus to separate the opened bags from the powder, and continuously operating said separating apparatus. 85

2. The method of salvaging explosive powder contained in small fabric bags and packed in sealed containers, consisting in 95 rotatably mounting each container in a holder and exerting a straight outward pull upon the free end of its sealing band to rotate the container and strip off the band, and performing in succession at widely spaced points the operations of passing the contents of the containers through an apparatus for opening the bags, through an apparatus for separating the powder from the opened bags, passing the powder through an apparatus for finally screening it, and passing the screened powder into an apparatus for charging it into containers and weighing it. 100

3. The method of salvaging explosive powder contained in small fabric bags and packed in sealed containers consisting in 110 mounting each container rotatably upon a holder and exerting an outward pull upon the free end of its sealing band to rotate the container and strip off the band, passing the contents of the container through a rotary cutting apparatus to cut open the bags, and screening the powder from the 115 opened bags. 120

4. The method of salvaging explosive powder contained in small fabric bags and packed in sealed containers consisting in 125 unloading the containers upon a platform from a car, mounting each container rotatably on a holder upon the platform and exerting a straight outward pull upon the the free end of its sealing band to rotate the container and strip off the band, delivering the contents of the containers over 130

a power-driven conveyor to a power-driven cutting apparatus to cut the bags open, passing the opened bags and powder over a power-driven conveyor to a power driven 5 screening apparatus for separating the bags from the powder, passing the screened powder over a conveyor to a second screening apparatus for separating the lint therefrom, passing the powder from the 10 second screening apparatus over a conveyor to a hopper located over a car-loading platform, admitting powder from said hopper to sacks placed upon a scale platform beneath the hopper to weigh the powder in 15 the sacks, and loading the weighed sacks of powder upon a car adjacent the loading platform.

5. An apparatus for salvaging explosive charges contained in small fabric bags, comprising power-driving rotary cutting means 20 to cut open the bags, a power-driven rotary screen disposed with its axis of rotation inclined and its opposite ends open, and an endless power-driven conveyor 25 adapted to receive the opened bags and powder from the cutting machine and deliver them into one of the said open ends of the screen, whereby the screen will separate the powder from the bags and 30 discharge the bags from its opposite open end.

6. An apparatus for salvaging explosive

charges contained in small fabric bags, comprising power-driven rotary cutting means to cut open the bags, a power-driven rotary screen disposed with its axis of rotation inclined and its opposite ends open, and means to deliver the opened bags and powder from the cutting means into one of the open ends of the screen, whereby the screen will separate the powder from 35 the bags and discharge the bags from its opposite open end.

7. An apparatus for salvaging explosive charges contained in small fabric bags, comprising a hopper to receive said bags, a rotary cutter to cut open the bags, means to continuously deliver the bags from the hopper to the cutter, a screen adapted to separate the opened bags from the powder, means to continuously deliver the opened 45 bags and powder from the cutter to said screen, a second screen adapted to remove the lint from the separated powder, a conveyor connecting said two screens, means to fill the finally screened powder into sacks 50 and weigh it, and a conveyor connecting said second screen with the said sack filling means.

In testimony whereof I hereunto affix my signature.

GUSTAVE ALLISON.
